RAILROAD RAIL SUPPORTING AND
SECURING MEANS

Levi Borden Armstrong, Great Neck, N. Y., assignor to The Lundie Engineering Corporation, New York, N. Y., a corporation of New York

Application October 22, 1940, Serial No. 362,203

7 Claims. (Cl. 238—349)

The present invention relates to railroad rail supporting and securing means characterized by a new and improved form and arrangement of cooperating tie-plate and clip by which a rail may be suitably secured in position on railroad ties.

A general object of the invention is to provide a tie-plate and cooperating clips which may be used for the securing of rails having bases of different widths, thereby reducing the number of sizes of tie-plates which it is necessary to manufacture and necessary for the railroads to carry in stock.

A particular object of the invention is to provide a tie-plate which is simple and economical to manufacture by reason of the omission of the ribs often provided on the top of tie-plates for engagement with one or both edges of the base of the rail. The omission of such ribs is made possible by the present invention by the provision of a clip having a downwardly extending lug which projects into an opening in the tie-plate and engages the edge of the rail base. These clips are secured to the tie-plate in any suitable manner but preferably by a screw bolt which passes through a hole in the clip and a hole in the tie-plate and into the railroad tie. The hole in the clip through which the screw bolt passes may be of elliptical form so that the clip may be set at different positions on the tie-plate in cooperation with different widths of rail base; and if desired a crescent-shaped plug may be used to fill in a portion of said elliptical opening so as to provide for an abutting connection between the clip and the screw bolt when the clip is engaging the edge of a rail base which is narrower than the maximum width of base with which the tie-plate is intended to cooperate.

In the drawings there is shown a tie-plate which will afford good gripping engagement with the tie and with the rail base, will be as light as is consistent with proper strength, and will cooperate properly with the rail base either with or without the provision of a layer or pad of yielding material between the rail base and the tie-plate. To these ends the tie-plate shown is not only provided on its bottom surface with the usual stepped projections, but also with reinforcing portions spaced apart from one another and arranged beneath those portions of the tie-plate which lie under the edges of the rail base. Also, the top of the tie-plate, throughout the area which is to be covered by the rail base, is provided with cup-shaped depressions which not only result in economy of material but also co-

operate advantageously with the rail base and with any cushion or pad used between the rail base and the tie-plate.

The invention offers many advantages, among which the following may be mentioned: The elimination of upstanding ribs on the top of the tie-plate reduces the cost of the plate by saving steel, by reducing the cost of rolling-mill rolls, by eliminating the frequent checking of tolerances between ribs, by reducing the cost of punching which in tie-plates of the prior art often has to be accomplished through the upstanding ribs of the tie-plate, and in other ways. Elimination of upstanding ribs on the top of the tie-plate also has the advantage of permitting the use of the same size of plate with rails having different base widths, as above mentioned, and also provides the advantage that in making rail renewals the tie-plate may be left undisturbed on the tie.

The tie-plate of the present invention is particularly adapted and intended to be used with the unique spring clips hereinafter shown and described. These clips not only hold the rail in place on the tie-plate, but also bear firmly on the base of the rail and tend to prevent creeping of the latter. These clips may be punched out of a ribbon of heavy sheet steel; and they can be economically manufactured by a punch and die operation, or they may be cast or forged. One of the advantages of this spring clip is due to the fact that it may be secured to the tie by a single spike or screw bolt, although a second spike may be driven through the hole adjacent the downwardly extending lug, if that is thought desirable in some places as at railroad curves. Other novel features and advantages of the invention will be apparent to those skilled in the art.

The invention will be understood from the following description taken in connection with the accompanying drawings in which is illustrated a preferred form of the invention, and in which Fig. 1 is a top view of a tie-plate embodying the invention; Fig. 2 is a bottom view thereof; Fig. 3 is an elevation of the tie plate and clips, secured to a railway tie and cooperating with the base of a railway rail; Fig. 4 is a top view of the spring clip forming part of the invention; Fig. 5 is a sectional elevation on the line 5—5 of Fig. 4; Fig. 6 is a top view of a crescent-shaped plug which may be used in the elliptical hole in the clip; Fig. 7 is a side view of said plug; Fig. 8 is a top view of a modified form of spring clip; and Fig. 9 is an edge elevation thereof. Like

parts are referred to throughout the drawings by the same reference characters.

The form of the tie-plate which is part of the present invention will be understood from Figs. 1, 2 and 3. As will be apparent from the drawings, the tie-plate is ribless, that is, it does not have on its top side the rib or ribs usually provided for engagement with one or both edges of the base of the rail to be supported. The tie-plate of the invention is provided with a central portion 8 having a width between the shoulders 9 and 10 substantially equal to the width of the widest rail base to be accommodated thereon. This central portion or rail-bearing area 8 of the tie-plate is provided with cup-shaped indentations 12 preferably arranged as shown in Figs. 1 and 3. The side portions of the tie-plate, outside the shoulders 9 and 10, are provided with four pairs of openings 13 and 14, the preferred form and arrangement of which are shown in Fig. 1, from which it is apparent that the outer openings 14 are circular and the inner openings are rectangular. The rectangular openings 13 are so arranged that the inside wall thereof is substantially on the lines where the edges of the narrowest rail base to be supported by the tie-plate will be. As will hereinafter appear, this permits the clips (hereinafter described) to engage with the edge of rail bases having different widths.

The form of the bottom of the tie-plate will be apparent from Figs. 2 and 3. As will be obvious, the bottom of the tie-plate is provided with stepped projections 16, and a plurality of reenforcing portions 17 (which may be of the form shown or any other suitable form) the surfaces of which meet in ridges lying in the plane of the edges of the projections 16 and are spaced apart from one another. Moreover, since the reenforcing portions 17 are arranged in those portions of the tie-plate which will lie under the edges of the base of the rail to be accommodated by the tie-plate, a strengthening of the tie-plate is provided at those portions where the tie-plate is subjected in use to the greatest strains.

The form and construction of the unique clips which are adapted to cooperate with the tie-plate hereinbefore described, will be apparent from Figs. 3, 4 and 5. As shown, the clip comprises a substantially straight body portion 20 having therein an opening 21 which is preferably elongated as shown in Fig. 4. Extending from the body portion 20 of the clip is an offset toe portion 22 provided with an end 23 adapted to cooperate with the top of a rail base. As will be apparent from Figs. 3, 4 and 5, the offset toe portion of the clip is provided with a lug 25 which is cut and bent out of said toe portion so as to provide a spike-receiving opening behind it and so as to extend substantially at right angles to the body portion of the clip and across the plane of the latter, as will be obvious from Fig. 5. As shown in Figs. 3 and 5, the body portion of the clip at the region of the opening 21 is preferably provided with an upward bulge.

The manner in which the clips are secured to and cooperate with the tie-plate is shown in Fig. 3. While any suitable fastener may be employed, either one of the forms shown in Fig. 3 is believed to be preferable. The form of fastener shown at the left of Fig. 3 consists of a screw bolt having a threaded end 30 adapted to screw into a hole drilled in the railroad tie 31; and a rectangular head 32 adapted

to receive a wrench, a collar 33 below said head being provided for engagement with the top of the bulged portion of the clip. Thus the substantially straight body portion of the clip lies parallel to and against the top of the tie-plate, the end 23 of the toe portion of the clip is held in cooperative engagement with the top of a rail base 34; and the lug 25, which projects into one of the inner openings 13 in the tie-plate, extends vertically across and against the edge of the rail base and prevents the clip from skewing. As will be apparent from Fig. 3, the rail base there shown is of the maximum width for which the tie-plate is intended; that is, the base of the rail extends from the shoulder 9 to the shoulder 10 of the tie plate. It will be obvious that when the clips are used with a rail having such maximum width, the side thrust of the rail which is taken by the lug 25 of the clip is transmitted directly to the securing screw bolt with which the wall of the elongated opening 21 which is nearest to the rail is in direct contact. If, however, the tie-plate and clips are used with a rail having a base of less width, for example the minimum width, the clips are then set at positions which leave a crescent-shaped opening between the screw bolt and the end of the elliptical opening 21 nearest the rail. If desired, such crescent-shaped space may be filled with a crescent-shaped plug 35 of the form shown in Figs. 6 and 7.

The bolt shown at the right side of Fig. 3 is shown as also provided with a threaded end 39' adapted to screw into a drilled hole in the tie 31, and with a square head 32' adapted to receive a wrench; but of course this bolt may be of a type adapted to be driven into the tie. As will be obvious from the drawing, the middle portion of said bolt is provided with threads carrying a nut 38 which may either directly engage with the top of the bulged body portion of the clip or may engage with a helical spring 39 interposed between the nut and said clip. The bolt arrangement shown at the right side of Fig. 3 holds the clip in proper position in engagement with the rail as in the case of the bolt shown at the left side of Fig. 3. While in most cases a rail will be securely held on the tie-plate by means of the clips and bolts shown in Fig. 3, it is of course possible to augment the fastening means by driving a spike into the tie through the opening behind the lug 25; but such additional securing means is not generally necessary.

When cushioning of the rail on the tie-plate is desired, for the purpose of eliminating noise and absorbing shocks, a pad 42 of resilient material, provided on its bottom with cup-shaped projections 43 adapted and arranged to register with the cup-shaped indentations 12 in the tie-plate, may be provided. When such a pad of resilient material is used, the clips hereinbefore described, serve particularly well to hold the rail base 34 in engagement with the pad, so that the rail base, pad and tie-plate adhere to one another more or less by suction due to the exclusion of air between the adjacent surfaces. In fact, even when the pad 42 is omitted, there may be some adherence by suction between the rail base 34 and the tie-plate due to the close contact between the surfaces of these which is promoted by the presence of the indentations 12 in the top of the tie-plate.

Figs. 8 and 9 show a modified form of spring clip which is adapted to cooperate with the tie-

plate hereinbefore described, and is particularly intended for use where the supported rail is subjected to great lateral forces as in the case on curves. As will be apparent from Figs. 8 and 9, the clip shown therein comprises a substantially straight body portion 50 (which if desired may be bulged as is the clip of Fig. 5) having therein openings 51 and 52 which are elongated as shown in Fig. 8. Extending from the body portion 50 of the clip is an offset toe portion 53 provided with an end 54 adapted to cooperate with the top of a rail base. At both sides of the offset toe portion of the clip, are lugs 55 and 56 which are cut and bent out of said toe portion so as to provide spike-receiving openings behind them and so as to extend at substantially right angles to the body portion of the clip and across the plane of the latter, as will be obvious from Fig. 9. It will be understood that the clip shown in Fig. 9 is secured to the tie-plate by any suitable fasteners, such for example as those shown in Fig. 3, with the end 54 of the toe portion of the clip in cooperative engagement with the top of the rail base, and with the lugs 55 and 56 extending vertically across and against the edge of the rail base and projecting into the inner openings 13 in the tie-plate. Therefore, the clip shown in Figs. 8 and 9 is highly effective in holding the rail on the tie-plate and resisting lateral movement thereof.

It will be apparent to those skilled in the art that the advantages set forth at the beginning of this specification, and others, are inherent in the rail-supporting and securing means which has been described as the best known form of the invention. However, it is to be understood that the constructions of tie-plate and clip which have been described may be modified without departing from the spirit of the invention as defined in the following claims.

What is claimed is:

1. Cooperating rail supporting and securing means comprising in combination a tie-plate having therein a plurality of pairs of inner and outer openings; and clips each adapted to cooperate with a pair of said openings in the tie-plate, each of said clips comprising a substantially straight body portion adapted to lie parallel to and against the top of the tie-plate and having an opening adapted to register with the outer opening of one of said pairs of openings in said tie-plate and to receive securing means, and a toe portion off-set from said body portion and provided with an end adapted to cooperate with the top of a rail base and having a lug cut and bent out of said toe portion thereby providing on the outer side of said lug another opening in said clip adapted to register with the inner opening of said pair of openings in said tie-plate and to receive securing means, said lug being adapted to extend vertically across and against the edge of a rail base and extend into said inner opening in said tie-plate.

2. Cooperating rail supporting and securing means comprising in combination a tie-plate adapted to support rails having bases of different widths, and having therein a plurality of pairs of inner and outer openings, the inner opening of each pair having its inside wall substantially on the line where the edge of the narrowest rail base to be supported by the tie-plate will be; and clips each adapted to cooperate with a pair of openings in the tie-plate, each of said clips comprising a substantially straight body portion adapted to lie parallel to and against the top of the tie-plate and having an opening adapted to register with the outer opening of one of said pairs of openings in said tie-plate and to receive securing means, and a toe portion off-set from said body portion and provided with an end adapted to cooperate with the top of a rail base and having a lug cut and bent out of said toe portion thereby providing on the outer side of said lug another opening in said clip adapted to register with the inner opening of said pair of openings in said tie-plate and to receive securing means, said lug being adapted to extend vertically across and against the edge of a rail base and extend into said inner opening in said tie-plate.
3. A clip adapted to cooperate with a railroad tie-plate for securing a rail thereon, comprising a substantially straight body portion adapted to lie parallel to and against the top of a tie-plate and having therein an opening adapted to receive securing means, and a toe portion off-set from said body portion and provided with an end adapted to cooperate with the top of a rail base and having a lug cut and bent out of said toe portion so as to provide another opening adapted to receive securing means and adapted to extend vertically across and against the edge of a rail base.
4. A clip as described in claim 3, in which the opening in the body portion is elongated.
5. A clip as described in claim 3, in which the body portion is bulged.
6. A clip adapted to cooperate with a railroad tie-plate for securing a rail thereon, comprising a substantially straight body portion adapted to lie parallel to and against the top of a tie-plate and having therein a plurality of openings adapted to receive securing means, a toe portion off-set from said body portion and provided with an end adapted to cooperate with the top of a rail base and a plurality of lugs cut and bent out of said toe portion so as to provide openings adapted to receive securing means and adapted to extend vertically across and against the edge of a rail base.
7. A clip as described in claim 6, in which the openings in the body portion are elongated.

LEVI BORDEN ARMSTRONG.
